DESIGN FOR A STEREOSCOPIC VIEWER

Earl Rossman, New York, N. Y., assignor to Novelview, Inc., New York, N. Y., a corporation of New York

Application September 25, 1935, Serial No. 58,703

Term of patent 14 years

To all whom it may concern:

Be it known that I, Earl Rossman, a citizen of the United States and resident of New York, in the county of New York and State of New York, have invented a new, original, and ornamental Design for Stereoscopic Viewers, of which the following is a specification, reference being had to the accompanying drawing, forming part thereof.

Fig. 1 is a front elevation of the stereoscopic viewer, showing my new design.

Fig. 2 is a plan view of the stereoscopic viewer shown in Fig. 1.

I claim:

The ornamental design for a stereoscopic viewer, as shown.

Signed at New York, in the county of New York and State of New York, this 23rd day of September, A. D. 1935.

EARL ROSSMAN.
